CLAIM

USPC **D23/304**; D24/176

We claim the ornamental design for a mounting bracket for a water flosser, substantially as shown and described.

(58) **Field of Classification Search**

DESCRIPTION

USPC D24/128, 152, 176–178, 111; D23/223, D23/228, 242, 249, 270–271, 303–304; D6/512, 524; 4/546, 552, 596, 605, 4/615, 695; 137/801; 248/75; 601/162

FIG. 1 is a front, right isometric view of a mounting bracket for a water flosser.

See application file for complete search history.

(56) **References Cited**

FIG. 2 is a front elevation view of the mounting bracket of FIG. 1.

U.S. PATENT DOCUMENTS

FIG. 3 is a rear elevation view of the mounting bracket of FIG. 1.

203,094 A	4/1878	Wakeman
428,023 A	5/1890	Schoff
445,250 A	1/1891	Lawless

1,018,143 A	2/1912	Vissering
1,193,302 A	8/1916	Seltner

FIG. 4 is a right side elevation view of the mounting bracket of FIG. 1.

FIG. 5 is a left side elevation view of the mounting bracket of FIG. 1.

FIG. 6 is a top plan view of the mounting bracket of FIG. 1; and,

FIG. 7 is a bottom plan view of the mounting bracket of FIG. 1.

The broken lines, which define the bounds of the claimed design, form no part of the claimed design.
